UNITED STATES PATENT OFFICE

109,350

DESIGN FOR A CONCEALED HINGE BRACKET

Morton Tucker, Haddonfield, N. J.

Application February 8, 1938, Serial No. 74,961

Term of patent 14 years

To all whom it may concern:

Be it known that I, Morton Tucker, a citizen of the United States and a resident of Haddonfield, in the county of Camden and State of New Jersey, have invented a new, original, and ornamental Design for a Concealed Hinge Bracket, of which the following is a specification, reference being had to the accompanying drawing forming a part thereof and in which

I claim:

The ornamental design for a concealed hinge bracket, substantially as shown.

MORTON TUCKER.
